BEADING MACHINE

Eugene E. Bryant, Cleveland, Ohio, assignor to
 Ferro Enamel Corporation, Cleveland, Ohio, a
 corporation of Ohio

Application December 1, 1938, Serial No. 243,443

2 Claims. (Cl. 91—12)

This invention relates, as indicated, to a bead enameling machine and more specifically to a machine for applying a band of enamel slip to the bead, flange, or lip of either the usual substantially circular enamel ware or ware with well rounded corners.

It has long been customary to ornament the lip or bead of enamel ware utensils and the like with a band of colored enamel in order to give a more attractive and finished appearance to the final product. In the past this band or stripe, generally termed the "bead" in the enamel industry, has been applied entirely by hand, using the fingers or a brush. This is not only a relatively slow and expensive operation in an otherwise rather completely mechanized industry, but also the "beads" on finished articles of any one type are far from uniform as to width, smoothness, and weight of application of the slip. Enamelware utensils are produced in very large quantities and in a great variety of shapes and sizes so that even a slight saving in time and cost per unit becomes important.

The principal object of this invention is to provide a machine for the application of enamel-ware of a band or "bead" of enamel slip uniform not only on individual pieces but also as between any two pieces of a given type.

A still further object is to provide a machine by which a better enamel bead may be applied at less cost and at greater speed than is at present done by hand.

Other objects of the invention will appear as the description proceeds.

To the accomplishment of the foregoing and related ends, said invention, then, consists of the means hereinafter fully described and particularly pointed out in the claims; the annexed drawing and the following description setting forth in detail certain means and one mode illustrating, however, but one of the various ways in which the principle of the invention may be used.

In said annexed drawing:

Fig. 1 is a front elevational view of one embodiment of my invention; and

Fig. 2 is a side elevational view of such embodiment.

My invention comprises a new method of applying a bead or band of enamel slip to the lip of a piece of enamelware by rotating the work with its lip in engagement with a transfer wheel, hereafter called the enamel wheel, a portion of the periphery of which dips into a bath of enamel slip. This invention also comprises a

new machine for applying a bead or band of enamel slip to the lip of a piece of ware.

Referring now more specifically to the drawing, the apparatus illustrated is a preferred embodiment comprising a rotatable shaft 1' driven by a pulley 2' and carrying an enamel wheel 3', which dips into the tank 4' containing the enamel slip to be used in beading the ware. Said shaft 1' also carries a rubber-tired wheel 23 of the same diameter as the enamel wheel 3'. The rotatably mounted hollow shaft 5' is supported in its housing 6' above said shaft 1' by the arms 24 and 25 pivotally mounted on a stationary bar 26. Arm 24 is extended beyond said bar 26 and at its further end carries a counterweight 27 to partially balance the weight of the housing 6' and the parts supported thereby. The arm 24 is also connected at a point between the rod 26 and its further end to a foot pedal 14' by means of a series of links and levers. The hollow shaft 5' carries a suction head 16' (adapted to fit the ware 18'') and communicates with the substantially air-tight housing 6' which is connected with a vacuum line 9' and a vacuum release valve 10'. Said valve 10' is mounted adjacent a stop 11' attached to the supporting bar 26 and has a valve handle 12' which, upon the raising of the housing 6', is caused to strike said stop 11' and open said valve. Mounted on shaft 5' above the wheel 23 is a grooved wheel 28 of the same size and contour as the ware to be beaded.

Thus, when there is no pressure being exerted on the pedal 14' the two wheels 23 and 26 will be in contact and shaft 5' will be driven so that the ware 18'' turns with the enamel wheel 3'' without slipping. When pressure is exerted on the foot pedal 14' the housing 6' is elevated, lifting the ware from contact with the enamel wheel 3'' and the grooved wheel 28 from contact with the tired wheel 23. When the housing has been sufficiently elevated the valve handle 12' will strike the stop 11', open the valve 10' and release the suction which holds the ware in position. By altering the size and shape of wheel 28 to conform to the type of ware being beaded, a large variety of ware may be handled.

It is obvious that various changes may be made in my device without in any way departing from the fundamental principles of my invention. Since the enamel wheel does not revolve very rapidly, it is possible to operate my device manually, although some other source of power is preferred if maximum output is desired. The ware may also be held in position by hand by pressing it against a rubber gripping means instead of

employing suction or an electromagnet. The advantages of the latter are apparent, however. The machine of Figs. 1 and 2 may be constructed so that upon lowering the upper shaft 5' the wheel 28 will make contact with the wheel 23 before the ware touches the enamel wheel, thus causing the ware to be rotating when it contacts the enamel wheel. This may be accomplished by providing means for tipping shaft 5' slightly.

The slip is the usual enamel slip and may be made up with water or any other suitable suspension medium. The angle of contact and the type of enamel wheel together with the viscosity of the enamel slip will determine the width of bead applied to the dry bisque ware and also the weight of application.

Other modes of applying the principle of the invention may be employed, change being made as regards the details described, provided the features stated in any of the following claims, or the equivalent of such, be employed.

I therefore particularly point out and distinctly claim as my invention:

1. A bead enamelling machine comprising a rotatable shaft with actuating means for rotating said shaft, an enamel wheel mounted thereon, an enamel slip tank into which said enamel wheel dips, a second rotatable shaft elevately mounted above said rotatable shaft and provided with ware-holding means above said

enamel wheel, means to elevate and lower said second shaft driving means comprising a tired wheel of the same diameter as the said enamel wheel and mounted on the same said rotatable shaft and a grooved wheel of the same size and contour as the circumference of the ware to be beaded mounted on said second shaft, said tired wheel and said grooved wheel being in driving and driven contact when the second rotatable shaft is lowered so that the ware contacts said enamel wheel.

2. A bead enamelling machine comprising a rotatable shaft with actuating means for rotating said shaft, an enamel wheel mounted thereon, an enamel slip tank into which said enamel wheel dips, a second rotatable shaft elevately mounted above said rotatable shaft and provided with ware-holding means above said enamel wheel, means to elevate and lower said second shaft driving means comprising a wheel of the same diameter as the said enamel wheel and mounted on the same said rotatable shaft and a wheel of the same size and contour as the circumference of the ware to be beaded mounted on said second shaft, and wheels being in driving and driven contact when the second rotatable shaft is lowered so that the ware contacts said enamel wheel.

EUGENE E. BRYANT.
